DESIGN FOR A LATCH UNIT

Walter G. Dieter, Williamsport, Pa., assignor to
Libbey-Owens-Ford Glass Company, Toledo,
Ohio

Application May 26, 1945, Serial No. 119,747

Term of patent 14 years

(Cl. D50—5)

To all whom it may concern:

Be it known that I, Walter G. Dieter, a citizen of the United States, residing at Williamsport, in the county of Lycoming and State of Pennsylvania, have invented a new, original, and ornamental Design for a Latch Unit, of which the following is a specification, reference being had to the accompanying drawing, forming part thereof.

Fig. 1 is a front elevational view of a latch unit showing my new design; and

Fig. 2 is a top plan view thereof.

This is a division of my copending application Serial No. D-112,509, filed February 8, 1944, entitled "Design for toilet stall closure."

I claim:

The ornamental design for a latch unit, as shown.

WALTER G. DIETER.
